Patented Oct. 20, 1959

186,360

SURFACE TREATING MACHINE FOR CLEANING CARPETS OR THE LIKE

Robert A. Yonkers and Henry T. Lathrop, Grand Rapids,
Mich., assignors to Bissell Carpet Sweeper Company,
Grand Rapids, Mich., a corporation of Michigan

Application October 11, 1957, Serial No. 48,066

Term of patent 14 years

(Cl. D9—2)

Figure 1 is a perspective view of a surface treating machine for cleaning carpets or the like embodying our new design;

Figure 2 is a reduced side elevational view thereof; and

Figure 3 is an enlarged cross-sectional view on line 3—3 of Figure 2.

The opposite side of the machine is substantially the same in appearance as the side shown.

We claim:

The ornamental design for surface treating machine for cleaning carpets or the like, as shown and described.
